UNITED STATES PATENT OFFICE.

FREDERICK L. RE QUA, OF MILWAUKEE, WISCONSIN, ASSIGNOR TO THE CUTLER-HAMMER MFG. CO., OF MILWAUKEE, WISCONSIN, A CORPORATION OF WISCONSIN.

CURRENT-REGULATOR.

1,390,543.

Specification of Letters Patent. Patented Sept. 13, 1921.

Application filed August 19, 1918. Serial No. 250,421.

To all whom it may concern:

Be it known that I, FREDERICK L. RE QUA, a citizen of the United States, residing at Milwaukee, in the county of Milwaukee and State of Wisconsin, have invented new and useful Improvements in Current-Regulators, of which the following is a full, clear, concise, and exact description, reference being had to the accompanying drawing, forming 10 a part of this specification.

This invention relates to current regulators for incandescent lamps and other translating devices.

One of the objects of the invention is to 15 provide a simple and efficient current regulator obviating the necessity for regulating resistances and hence obviating the waste of energy incident to the use of such resistances.

20 Another object is to provide a regulator of the aforesaid character affording a continuous variation of current as distinguished from a step by step variation.

Another object is to provide regulating 25 means particularly adapted for installations requiring economy of space.

A further object is to provide regulating means particularly adapted for remote control.

30 Other objects and advantages will herein-after appear.

The accompanying drawing diagrammatically illustrates certain embodiments of the invention particularly adapted for lamp 35 regulation and the same will now be described, it being understood that the embodiments illustrated are susceptible of various modifications and that certain features thereof may be utilized in regulating various 40 other translating devices.

Figure 1 diagrammatically illustrates one embodiment of the invention; and

Fig. 2 diagrammatically illustrates a modification of the embodiment shown in 45 Fig. 1.

Referring to the drawing, the same shows a bank of incandescent lamps 1 supplied with current by an A. C. generator 2, and regulating means including a magnetic amplifier 3 and a commutator 4 driven by a motor 5 to control said amplifier in a manner hereinafter described.

The magnetic amplifier 3 is of a well-known type having alternating current 50 windings 6 and 7 and a direct current winding 8, the former windings being respec-

tively wound on magnetic cores 9 and 10 and the latter winding being wound on adjacent portions of the two cores. The windings 6 and 7 are connected in series with one another and included in the lamp circuit whereby, as will be understood, the current flowing in the lamp circuit is subjected to regulation by the winding 8. More specifically, the winding 8 inductively influences 65 the windings 6 and 7 to regulate the flow of current through the latter windings according to the amount of current supplied to the former winding. The winding 8 is supplied with current from a constant potential direct current circuit $L' - L^2$ and for control in the manner hereinafter specified, is provided with a local circuit including a capacity 11 although said capacity might be replaced by a resistance 12, as shown in 70 Fig. 2.

The commutator 4 comprises two segments 13 and 14 and two brushes 15 and 16, one or both of said brushes being adjustable rotatively of said commutator. The segments 13 and 14 are insulated from one another and rotatable by the motor 5 which is shown as of the shunt type and as supplied with current from the circuit $L' - L^2$. The commutator is interposed between one terminal 80 of the winding 8 of the magnetic amplifier and the supply circuit, i. e., the brush 16 is connected to the winding 8 and the brush 15 to the supply circuit whereby the brushes must be bridged by one of the commutator segments to complete the circuit of said winding. Also, the brushes 15 and 16 have a capacity 17 connected therebetween to minimize sparking upon interruption of the 85 circuit of winding 8 by the commutator. 90

With this arrangement the commutator will intermittently subject the winding 8 to the potential of circuit $L' - L^2$ while said winding which is inductive will discharge back through the capacity 11 or resistance 12 when its circuit is interrupted and the current thus supplied to said winding will be a function of the intermittency of the impressed voltage. More specifically, by properly proportioning the electrical constants of the circuits the current through the winding 8 will be substantially constant for a given applied potential and a given ratio of the time of potential application to the total time required for one cycle of operation of the commutator, whereas a variation in said ratio will vary the current through 100 105 110

said winding. Also, the current through the winding 8 may be varied by varying the speed of rotation of the commutator as by variation of the speed of motor 5 through the medium of a field rheostat R. Where the shunt for the winding 8 comprises a resistance, the speed of rotation of the commutator above a critical value will have little or no effect on the current through said winding but where said shunt comprises a capacity the current through said winding may be varied over a considerable range and in practice the current may be varied by both of the aforesaid methods.

15 As will be apparent, the aforesaid ratio may be varied by relative adjustment of the commutator brushes. When the angular displacement of the brushes about the commutator is 180° the winding 8 will receive no 20 potential and consequently no current will flow therethrough. On the other hand, when the angular displacement of the brushes is increased or decreased the winding 8 will be intermittently subjected to a potential for 25 periods determined by the relative adjustment of said brushes and accordingly will receive current of a value approximately proportional to the ratio of the time of potential application to the total time required 30 for one revolution of the commutator.

Assuming the desirability of controlling a translating device having an inductive regulating winding, it is to be understood that the means illustrated for controlling the 35 winding 8 might be employed to directly control such translating device.

Further, it is to be understood that while the commutator is illustrated as having but two segments for commutations upon half 40 revolutions, said commutator might be provided with any preferred number of segments for reduction of the degree of rotation required for successive commutations.

What I claim as new and desire to secure 45 by Letters Patent is:

1. In a current regulator, the combination with a magnetic amplifier having coördinated alternating and direct current windings, of a local circuit for the direct current 50 winding of said amplifier and means for subjecting said last mentioned winding to a given potential intermittently.

2. In a current regulator, the combination with a magnetic amplifier having coördinated alternating and direct current windings, of a local discharge circuit for the direct current winding of said magnetic amplifier and means for subjecting said last 55 mentioned winding to a given potential intermittently and varying the duration of the periods during which such potential is applied to said direct current winding.

3. In a current regulator, the combination with a magnetic amplifier having coördinated alternating and direct current wind-

ings, of a shunt for the direct current winding of said magnetic amplifier and means for subjecting said last mentioned winding to a given potential intermittently and varying the ratio of the time of application of 70 such potential to the total time of one cycle.

4. In a current regulator, the combination with a magnetic amplifier having coördinated alternating and direct current windings, of a shunt circuit for the direct current winding of said magnetic amplifier, a constant potential source of current for said direct current winding and a commutator to periodically establish and interrupt connections between said direct current winding 75 and said source, said commutator having brushes relatively adjustable to vary the duration of the periods during which such connections are established relatively to those during which such connections are interrupted.

5. In a current regulator, the combination with a magnetic amplifier having coördinated alternating and direct current windings, of a local discharge circuit for said direct current winding, a constant potential source of current for said direct current winding and means to periodically establish and interrupt circuit between said direct current winding and said source, said means 90 being adjustable to vary the frequency of interruption and establishment of such circuit.

6. In a current regulator, the combination with a magnetic amplifier having coördinated alternating and direct current windings, of a local discharge circuit for said direct current winding, a constant potential source of current for said direct current winding and means to periodically establish 100 and interrupt circuit between said direct current winding and said source, said means being adjustable to vary the frequency of interruption and establishment of such circuit and also being adjustable to vary the 110 duration of the periods during which such circuit is established relatively to those during which such circuit is interrupted.

7. The combination with an alternating current circuit, of regulating means therefor including an amplifying device having a plurality of windings, certain being connected in said circuit and another to be supplied with direct current, a capacity connected across the terminals of said latter 115 winding, a constant potential source of current for said latter winding and means to periodically establish and interrupt circuit between said latter winding and said source, said means being adjustable to vary the frequency of interruption and establishment of such circuit.

In witness whereof, I have hereunto subscribed my name.

FREDERICK L. RE QUA.
